Term of patent 14 years

(Cl. D33—14)

FIG. 1 is a perspective view of a furniture base embodying the design.

FIG. 2 is a reduced side elevational view thereof.

FIG. 3 is a reduced top plan thereof.

The design is characterized by the combination composed of an inverted hollow cone in association with four equally spaced and outwardly extending leg members, said leg members being integral with the inverted cone and attached thereto at points slightly above the smaller end portion of the furniture base, all as shown.

I claim:

The ornamental design for a furniture base, as shown and described.
